CYRILL PARENT, OF ANDOVER, MASSACHUSETTS, ASSIGNOR TO CROMPTON & KNOWLES LOOM WORKS, OF WORCESTER, MASSACHUSETTS, A CORPORATION OF MASSACHUSETTS.

SUPPORT FOR LOOM PICKING SPINDLES.

Application filed December 18, 1926. Serial No. 155,742.

This invention relates to improvements in loom picking spindles and supporting means therefor and it is the principal object of the invention to provide means for securing 5 the inner end of the picking spindle in definite relation with respect to the reed and the path along which the shuttle moves.

In certain types of picking motions the shuttle is engaged by a picker which slides 10 along a spindle mounted usually behind the shuttle box, the picker stick moving the picker along the spindle and the latter guiding the picker independently of the lateral movements of the picker stick. Such constructions are common on box looms and 15 may also be used on the plain end of automatic looms. It is highly desirable to keep the axis of the spindle parallel to the path followed by the shuttle and it is accordingly 20 an important object of my invention to provide a clamping means for the inner end of the spindle to hold the latter tightly and prevent the same from working loose during the normal running of the loom.

25 The inner ends of spindles have heretofore been made conical to assist in centering them in the pocket provided in the lay. This construction involves an extra operation in the preparation of the spindle and also permits the spindle to get out of proper alignment due to the fact that the axis of the cone may not coincide with the axis of the 30 spindle. It is a further object of my invention to provide a mounting for the spindle rendering unnecessary the conical tip.

More specifically it is an object of my invention to provide a clamp having resilient members which can be forced against the inner end of the spindle by means of inclined surfaces, some part of the mechanism being formed as a wedge so that movement of the support in the direction of the axis of the spindle will move the resilient members tightly against said spindle to hold it 45 firmly in place.

With these and other objects which will appear as the description proceeds, my invention relates to the arrangements and combinations of parts hereinafter set forth, and more particularly pointed out in the 50 claims.

In the accompanying drawings, wherein two forms of the invention are shown,

Fig. 1 is a top plan view of one end of a lay having my invention applied thereto, 55

Fig. 2 is a rear elevation taken in the direction of arrow 2 of Fig. 1,

Fig. 3 is an enlarged vertical section on line 3—3 of Fig. 1, parts being broken away for the sake of clearness, 60

Fig. 4 is an enlarged vertical transverse section on line 4—4 of Fig. 3, and

Fig. 5 is a detail fragmental vertical section similar to a portion of Fig. 3 but showing a modified form of the invention. 65

Referring to the drawings the lay 10 has a lay end 11 secured thereto and may be supported by swords one of which is indicated at 12 in Fig. 2 and box guides 13 receive the tongues 14 of shuttle boxes 15. Said boxes accommodate shuttles S and may be raised and lowered by mechanism not shown, but well understood, so that one or the other of the shuttles will be active each 70 pick of the loom. 75

The spindle 16 is supported on the outer end by a block 17 bolted or secured in any other manner to the lay end and said spindle is held in adjusted longitudinal position by set screw 18. A picker 19 is moved along 80 the spindle by picker stick 20 and is provided with a shuttle engaging portion 21 which extends through a slot 22 formed in the lay end and also through the back wall of the boxes. When the loom is on so-called 85 "top center" the picker stick 20 is given an inward movement to the right from position shown in Figs. 1 and 2, and the picker 19 moves the active shuttle and is also guided on the spindle 16. 90

My improvement relates more particularly to the spindle and the device for holding the same and in carrying out my invention I make use of the lug 30 which is usually present in looms of the type having a picker spindle. In the preferred form of my invention, shown particularly in Fig. 3, I provide said lug with a cylindrical bore 31 and fit in the same the solid cylindrical shank 32 of a clamping member designated generally 100 at 33. The inner end of said member may be reduced and threaded as at 34 to receive a locking nut 35. The outer or left hand end of the clamp is provided with a cylindrical bore 36 which receives the inner end 105 of the spindle 16, the spindle in this instance

having a square end and not being provided with the usual taper.

As shown in Figs. 3 and 4 the left end of the clamp is provided with a conical outer surface 37 and said end is further provided with a plurality of transverse slots 38 which divide the conical end into a plurality of resilient clamping members 39. A collar 40 surrounds the inclined part of the clamping member and has a conical bore 41 to fit the conical surface 37. Said collar has close engagement with the left hand vertical wall of the lug 30 as shown clearly in Fig. 3.

In assembling the preferred form of the invention the shank of the clamping member will be inserted through the collar and into the bore 31 of the lug 30, after which the inner end of the spindle will be inserted in the split portion of the clamp. The nut 35 will then be threaded on end 34 and tightened to draw the conical end 37 to the right along the inner conical face 41 of the collar. This movement clamps the resilient portions 39 tightly against the spindle and holds the latter in place. When it is desired to loosen the spindle the nut 35 may be loosened and the members 39 will spring away from and release the inner end of the spindle.

The modified form of the invention shown in Fig. 5 operates on the same principle as does the preferred form, but the collar is eliminated. The lug 30, instead of having a cylindrical bore as illustrated in Fig. 3, has a bore a portion of which is cylindrical as indicated at 50 and a portion of which is conical as indicated at 51, Fig. 5. The clamping member 52 has resilient separated members 53 which correspond to the members 39 of the preferred form, and a threaded shank 54 extending from the modified clamp is provided with a nut 55. In this form of the invention tightening nut 55 will draw the clamp into the conical bore 51 so that the members 53 will be clamped tightly against the spindle 16. As shown in Fig. 5 the small diameter of the cylindrical bore 50 is somewhat greater than the small diameter of the body of the clamp so that said body, shown in section of said figure, will be free to move to the right to permit compression of the members 53, a condition which would not exist should the bore 51 be formed conically throughout its length.

From the foregoing it will be seen that the clamp acts to hold the spindle tightly in proper position with respect to the lay. It will further be seen that the spindle may be made with a square end, thus avoiding the expense of providing the same with a conical tip.

Having thus described my invention it will be apparent that changes and modifications may be made therein by those skilled in the art without departing from the spirit

and scope of the invention, and I do not wish to be limited to the details herein disclosed but what I claim is:

1. In a picker spindle mounting for loom lays, means to support the outer end of the spindle, a clamp for the inner end of the spindle having a bore to receive the inner end of the spindle and said clamp having a plurality of clamping members integral therewith and capable of slight movement relatively to the clamp, means forming an inclined surface on the clamp, means relatively stationary with respect to the lay presenting other inclined surfaces to correspond with and lying in contact with the first named inclined surfaces, and means to produce relative movement between the inclined surfaces to cause the clamping members to have tight engagement with the spindle.

2. In a picker spindle mounting for loom lays, means carried by the lay to support the outer end of the spindle, a clamping member supported by the lay for the inner end of the spindle and having a pocket into which the spindle projects, said lay and clamp having cooperating inclined surfaces and said clamp having resilient portions adjacent its inclined surface to engage the spindle, and means to produce relative movement of the surfaces, whereby said resilient portions of the clamping member will be forced tightly against the spindle.

3. In a picker spindle mounting for loom lays, means to support the outer end of the spindle, a clamping support for the inner end of the spindle, said support having a bore to receive the inner end of the spindle and said support being split so as to provide a plurality of integral members surrounding the inner end of the spindle, and means defining inclined surface on the clamping support and lay to force said members against the spindle as the clamping member is moved in a direction longitudinally of the spindle.

4. In a picker spindle mounting for loom lays, means carried by the lay to support the outer end of the spindle, a clamping member for the inner end of the spindle having a bore of variable diameter to receive the inner end of said spindle, cooperating conical surfaces formed on the clamp and the lay, and means to produce relative movement between said conical surfaces to cause a variation in the diameter of the bore, whereby said spindle will be clamped tightly or released, depending upon the direction of said relative movement.

5. In a picker spindle mounting for loom lays, means to support the outer end of the spindle, a clamping member for the inner end of the spindle having compressible elements surrounding a bore to receive said spindle, means defining surfaces on the clamping member inclined with respect to

- the axis of the spindle, means normally stationary with respect to the lay defining other surfaces inclined with respect to the axis of the spindle and having contact with the first named inclined surfaces, and means to produce relative movement between the clamping member and the means defining the second named inclined surfaces to compress said compressible elements of the clamp against the spindle to hold the latter firmly with respect to the lay.
6. In a picker spindle mounting for loom lays, means to support the outer end of the spindle relatively to the lay, a clamping member mounted on the lay for the inner end of the spindle, said clamping member having a cylindrical bore to receive the end of the spindle, portions of the clamping member adjacent the bore being split to provide a plurality of integral resilient elements, inclined surfaces formed on the outer sides of the elements, means fixed relatively to the lay and having interior inclined surfaces to receive the inclined outer surfaces of said elements, and means to cause relative movement between said elements and inclined interior surfaces in the direction of the length of the spindle to cause said elements to be clamped tightly against the spindle.
7. A picker spindle clamp for a loom lay having inclined surfaces normally fixed relatively thereto, said clamp having inclined surfaces to co-act with the inclined surfaces of the lay and having slightly yieldable spaced members integral therewith defining a bore for one end of the spindle said inclined surfaces of the clamp to cooperate with those of the lay to cause the yieldably spaced members to grip the spindle.
8. A picker spindle clamp for a loom lay having inclined surfaces, said clamp having a bore for one end of the spindle surrounded by a plurality of spaced slightly yieldable members integral with said clamp the outer surfaces of which are inclined to engage the inclined surfaces of the lay.
9. In a picker spindle mounting for a loom having a lay, a support for the outer end of the spindle, means defining inclined surfaces normally fixed relatively to the lay, a clamp for the inner end of the spindle having spaced yieldable members integral therewith and said clamp having inclined surfaces to cooperate with the inclined surfaces normally fixed relatively to the lay, and means engaging a portion of the lay and cooperating with the clamp to draw the inclined surfaces of the clamp along the inclined surfaces normally fixed relatively to the lay to force the members against the inner end of the spindle, said means holding the inner end of the spindle and clamp fixed relatively to the lay independently of the support for the outer end of the spindle.
10. In a picker spindle support for the lay of a loom, means fixed relatively to the lay and defining inclined surfaces, and a clamp having yieldable spaced clamping members for one end of the spindle, said clamping members having inclined surfaces co-operating with the inclined surfaces fixed relatively to the lay and said inclined surfaces co-acting when the spindle is moved toward the clamping members to cause said spaced clamping members to grip the spindle.

In testimony whereof I have hereunto affixed my signature.

CYRILL PARENT.
